Inventor:

William V. De Lap,
By appointment of, Christian Miles,
Attala, Miss.

UNITED STATES PATENT OFFICE.

WILLIAM V. DE LAP, OF MADISON, WISCONSIN, ASSIGNOR TO FRENCH BATTERY COMPANY, OF MADISON, WISCONSIN, A CORPORATION OF WISCONSIN.

FLASH LIGHT.

Application filed August 16, 1924. Serial No. 732,499.

This invention relates particularly to flash-lights; and the primary object is to provide a simple, cheap, and effective construction, rendering unnecessary the use of 5 a switch on the side of the casing.

The invention is illustrated in its preferred embodiment in the accompanying drawing, in which—

Figure 1 represents a longitudinal sectional view of a flash-light embodying the invention, the tubular cardboard cover for the cell being shown brokenly, and the parts being in such position that the circuit is broken, the section being taken as indicated at line 1 of Fig. 3; Fig. 2, a broken longitudinal sectional view showing the parts in position with the circuit closed; and Fig. 3, a horizontal sectional view taken as indicated at line 3 of Fig. 1.

In the construction illustrated, A represents a casing which may be of any suitable material, but which is shown as composed of hard fibre, or other insulating material; B, a battery contained in the casing; C, a reflector mounted in one end of the casing, in which is mounted a lamp C'; D, a lens, or glass, which bears against the outer end of the reflector and is secured in position by an annular threaded member D'; E, a metallic cap applied to the other end of the casing and equipped with a central contact stud E'; F, an insulating washer disposed beneath the battery B; and G, a coil-spring interposed between the cap E and the insulating disk F.

The casing is equipped at one end with a metallic ferrule 1 which is threaded and which has applied thereto the threaded ring, or retainer, D'.

The casing is equipped at the opposite end with a metallic ferrule 2 which is threaded and which has applied thereto the cap E.

A conductor strip 3 disposed adjacent the inner surface of the casing extends from one end of the casing to the other end and is connected with the ferrules by rivets 4. The upper end of the strip 3 is curved and provides a contact 5 which is in such position that contact will be made between the reflector and the point 5 when the reflector is forced inwardly by screwing the retainer D' down. If desired, the contact 5 may remain in contact with the reflector, even when 55 the circuit is broken at the base end of

the flash-light. The insulation disk F is provided with a central perforation 6 adapted to admit the free end of the contact stud E', so that the lower end of the battery may bear against said stud and complete 60 the circuit. The battery B may comprise one or more dry cells. In the illustration given, three cells 7 are illustrated, these cells being contained in the pasteboard tube, or carton 7a. The dry cells may have the outer electrode composed of a zinc cup, the bottom of the cup of the lowermost cell being adapted to contact with the upper end of the stud E'. The cells are shown provided at their upper ends with contacts 8, the uppermost one of which contacts with the central contact of the lamp bulb. When the retainer D' is screwed down, pressure is transmitted through the reflector and lamp to the battery, which is thereby depressed against 75 the force of the spring G until contact is established between the upper end of the stud E' and the bottom of the battery. Contact is established, also, between the metallic reflector C and the upper end of the conductor 3 when the parts are in the position shown in Fig. 2. In such position, the circuit is closed and the lamp is lighted. The circuit may be broken by unscrewing the retainer. Obviously, the circuit may be 80 broken at the stud E', or at the contact 5, or at both points.

The construction renders unnecessary the use of a switch on the side of the casing, and, as a result, the cost of production is reduced. 90

The foregoing description has been given for clearness of understanding only, and no unnecessary limitations should be understood therefrom, but the appended claims 95 should be construed as broadly as permissible, in view of the prior art.

What I regard as new, and desire to secure by Letters Patent, is:

1. A flash-light comprising a casing, a cap mounted on one end of said casing, a retainer having screw connections at the other end of said casing, a reflector and surrounding lens engaged by said retainer, a lamp mounted in said reflector, a central contact mounted in said cap, a coil-spring mounted in said cap, an insulation disk engaging said spring and having an opening through which contact may be established between said central contact and the bottom 105 110

of the battery, and a conductor electrically connected with said cap and adapted to establish electric connection with said reflector.

5 2. In a flash-light of the character set forth, a casing, a cap removably mounted on one end thereof, a coil-spring mounted in

said cap, a central contact member rigidly mounted in said cap, and a movable insulation disk disposed above said spring and ¹⁰ having a perforation adapted to receive said central contact.

WILLIAM V. DE LAP.
